UNITED STATES PATENT OFFICE.

ROBERT HENRY DOUGLAS BARKLIE, OF PURLEY, ENGLAND.

ELECTRIC FUSE.

Application filed January 19, 1927, Serial No. 162,201, and in Great Britain October 5, 1925.

This invention consists in improvements in or relating to electric fuses capable of being operated by very small currents such, for example, as currents of 30 milliamperes 5 and less.

According to the present invention an electric fuse comprises a film of metal supported on an insulating backing, the thickness of the film being substantially not 10 greater than one five-thousandths of an inch.

The invention further comprises an electric fuse comprising a film of metal which is so thin that it is not self-supporting for the purpose required and which is mounted 15 on an insulating backing such, for instance, as paper.

The metal film may be prepared in any one of many ways and examples of some of the methods of manufacturing fuses according to the invention will now be described.

In the accompanying drawing the view illustrates one form of holder or mounting for the fuse of this invention.

In its simplest form a film of metal may be obtained by the known process of beating as practised in the gold-beater's art. For instance, a gold film may be beaten until it is of a thickness that will obtain when one-thousand square inches of the metal film 30 has a mass of one gramme i. e. thickness is approximately three millionths of an inch. A sheet of paper is coated with gum and the gold film prepared as above is laid on the paper. The composite sheet thus formed is dried and for this purpose it may be left in an oven at a temperature of 110° C. for approximately twelve hours.

The sheet may be then cut into strips of required size. It is found that a sheet having a metal film 2 cms. long and 0.11 cms. in width will carry a current of 30 milliamperes and will fuse at approximately 35 milliamperes. Experiments have shown that a fuse having the same length but a width of 0.2 cms. will carry a current of 60 milliamperes and will fuse at 80 milliamperes. Thus, fuses according to the invention will carry currents the value of which 50 is roughly in proportion to the width of the film.

The length of the film may be small say, for example, 0.2 cms. and in order to make fuses which will carry heavier currents,

several films of metal may be superimposed on the one paper backing so that they are employed in parallel; or several fuse lengths as above described may be employed in parallel as will be readily understood.

Other metals such as silver and copper can be employed and can be reduced in thickness to the required extent by beating; but of course they will not have identical fusing qualities with those of gold.

It may be therefore said that the invention comprises an electric fuse which consists of a metal film supported on an insulating backing, the thickness of the film being less than that which can be obtained by rolling as films having a thickness of the order above specified cannot be obtained by known commercial processes for rolling metal foil.

According to another method of preparing the fuse a thin layer of metal is electrolytically deposited on one surface of a soluble cathode. For instance, gold can be deposited on silver. Thereafter the cathode is treated with a solvent that will dissolve the cathode without attacking the metal film. In the specific case mentioned the silver electrode can be removed by nitric acid of 50% strength. This may be effected by first depositing the gold on a thin strip of silver which is floated on the solvent. After the silver has been dissolved the gold will be left floating on the surface of the solvent and the gold can then be drawn out on the surface of a sheet of glass or celluloid. Alternatively silver can be deposited on an electrode of aluminium and the latter then be dissolved in caustic soda to leave a film of silver floating on the solvent.

The upper surface of the gold or other metal film can be readily washed while it is on the glass or celluloid surface from which it has been removed from the solvent. In order to wash the under surface, the temporary support (the glass or celluloid sheet) is dipped into a bath of water at such an angle that although the support is immersed the gold or metal film will float off on to the surface of the water which will thereby wash the underside thereof. The metal film can be removed from the washing water and be re-washed in a similar manner as many times as may be found necessary and finally it is washed similarly in alcohol.

The metal film can then be pulled or lifted from the alcohol washing bath on to a film of paper or other insulating material that is prepared in such a manner that when dried 5 the metal film will adhere closely thereto.

According to a further method of preparing fuses in accordance with the present invention, the metal is applied to an insulating backing in a finely divided condition.

10 For instance it may be sprayed under pressure by well known processes and thereafter consolidated and rendered homogeneous by mechanical treatment such as rolling. The metal may be otherwise applied to the insulating backing in a finely divided condition and subsequently rendered homogeneous by rolling. Such methods are particularly suitable in the case of metals such as tin, 15 lead, or tin-lead alloys.

20 Another method consists in sputtering or flashing metal in a finely divided condition by an ionization process such as a positive ray discharge in vacuo. It is thought unnecessary to describe such processes in detail 25 as they are already well known and are used, for example, (for other purposes) in flashing a metal such as magnesium in the final treatment for the evacuation of thermionic tubes.

30 A still further method consists in boiling a mass of the metal from which the fuse is to be formed in an electric furnace such as a high frequency induction current furnace. The boiling metal vapour may be conducted 35 on to the surface of an insulating backing and be condensed thereon so as to afford a film of the thickness desired.

As another alternative method a thin film 40 of silver may be deposited on to the insulating backing from a silver compound (such as an ammoniacal solution of silver nitrate) by a chemical reducing agent (such as formaldehyde) as in the known art of forming silver mirrors.

45 When an electrolytic method of depositing the metal film is resorted to as described above a fine deposit can be obtained and the thickness of the film can be reduced considerably beyond that attained by other methods. 50 For instance in the case of gold the thickness can be reduced approximately to as little as one-tenth of that of the commercially beaten gold leaf above mentioned. Intermediate values can obviously be obtained by regulation of the time and rate of 55 deposit.

Other processes of obtaining the requisite thin film will come within the scope of the 60 present invention and the details of the several processes given above are examples only of the various methods by which the invention can be carried into effect.

A convenient method of mounting fuses 65 made in accordance with this invention comprises a clip having two jaws or gripping

elements spring pressed towards one another or clamped by means of a screw or other equivalent means. One element is of metal and the other is of rubber or some other compressible material so that the fuse is gripped by the metal element against the rubber element with the former in contact with the metal film constituting the fuse. 70

Referring now to the drawing, the above referred to mounting is illustrated in the figure and wherein the thin fuse layer of metal is indicated at 1. The fuse strip 1 at each end is held between metal elements or jaws 2 and 3 between which is interposed a strip of rubber 4, the strip 4 having a portion lying between the metal element 3 and the insulating backing of the fuse strip 1. The metal layer 1 of the fuse is thus held at each end in contact with the metal element 2. Each pair of metal elements 2 and 3, together with the interposed strip 4, is inserted in a metal end cap 5, and may be secured in the cap by brazing or the like. The elements or jaws 2 and 3 are shouldered 80 flush with the ends of the metal caps 5, so that the ends of the elements 2 and 3 which project outwardly from the shoulders engage in the opposite ends of a glass tube 6, or other insulating tube which hold the end caps and the elements 2 and 3 therein in spaced apart and insulating relation. The parts 2, 3 and 4 fit tightly within the ends of the insulating tube 6, so that the fuse strip 1 will be gripped firmly between the 90 parts at each end and provide a good electrical contact between the strip 1 and the elements 2. In assembling the fuse structure, one pair of metal elements 2 and 3, and the rubber or like compressible strip 4, may be secured within an end cap 5. One 100 end of the strip 1 may then be gripped between the parts 2 and 4 and the assembly inserted within one end of the tube 6. From the other end of the tube, the metal element 2 and the rubber strip 4 are then inserted so as to retain the end of the fuse strip 1 between them. Finally, the metal element 3 is forced into the end of the tube and the end cap 5 fitted over the parts. 110

For establishing electrical connection with the fuse, the tubular fuse assembly may be held between the contact springs 7 which are mounted in the insulating base 8 provided with binding posts and nuts 9 for making 120 electrical connection between the springs 7 and the terminals of an external electric circuit. 115

I claim:—

1. A method of manufacturing an electric fuse which consists in electrically depositing metal on to a soluble electrode so that the thickness of the metal is substantially not greater than that of commercially beaten gold, dissolving the electrode from the deposited metal and thereafter floating 125 130

- the metal film on to an insulating backing and removing the solvent from the composite sheet thus formed.
2. A method of manufacturing an electric fuse which consists in electrically depositing metal on to a soluble electrode so that the thickness of the metal is substantially not greater than that of commercially beaten gold, dissolving the electrode from the deposited metal, floating the metal film on a substantially rigid support and removing it thereby from the electrolyte, and thereafter, as often as may be required, immersing the support in a washing liquid in such a manner that the film floats off on to the washing liquid so that its underside is washed clear of electrolyte and subsequently
- floating the film on to a permanent insulating backing.
3. A method of manufacturing an electric fuse which consists in depositing metal on to a soluble support, thereafter dissolving said support and recovering the metal film on a backing.
4. A method of manufacturing an electric fuse which consists in depositing metal on to a support by a process whereby the thickness of the deposited metal film gradually grows, removing said metal film on to the surface of a liquid and subsequently recovering the film from the liquid on to a backing.

In testimony whereof I affix my signature.

ROBERT HENRY DOUGLAS BARKLIE.
